CLAIM

The ornamental design for a housing for an electronic device, as shown and described.

DESCRIPTION

This is an application for a new, original and ornamental design for a housing for an electronic device (for example, the electronic device shown and described in U.S. Design patent application Ser. No. 29/452,631, filed Apr. 18, 2013 and entitled “Electronic Device,” which is herein incorporated by reference) 5, of which the following is a specification, reference being had to the accompanying drawings, forming a part thereof.

FIG. 1 is a bottom front perspective view of a housing for an electronic device showing our new design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

1 Claim, 5 Drawing Sheets
